Des. 207,553
Patented May 2, 1967

207,553

MEASURING INSTRUMENT

Daijiro Yamamoto, Kawasaki, Japan, assignor to
Yeham Numata, Yokohama, Japan

Filed Nov. 19, 1965, Ser. No. 88,156

Claims priority, application Japan Oct. 8, 1965

Term of patent 14 years

(Cl. D52—6)

FIG. 1 is a top plan view showing my new measuring instrument;

FIGS. 2 and 3 are side views taken from the right and left sides of FIG. 1, respectively;

FIG. 4 is a bottom plan view; and

FIGS. 5 and 6 are end views taken from the right and left ends of FIG. 4, respectively.

I claim:

The ornamental design for a measuring instrument, as shown.
